UNITED STATES PATENT OFFICE.

HARRY D. LILLIBRIDGE, OF ZANESVILLE, OHIO, ASSIGNOR TO AMERICAN ENCAUSTIC
TILING CO., LTD., OF NEW YORK, N. Y., A CORPORATION OF NEW YORK.

CERAMIC PRESS.

Application filed March 21, 1921. Serial No. 454,038.

To all whom it may concern:

Be it known that I, HARRY D. LILLIBRIDGE, a citizen of the United States, residing at Zanesville, county of Muskingum, State of Ohio, have invented a certain new and useful Ceramic Press, of which the following is a specification.

This invention is a press especially designed for compressing clay materials in the production of articles such as saggers, the latter being commonly used in the tile industry for containing tiles during the operation of firing the same within kilns. Although the press is useful for the production of saggers, it is to be distinctly understood that the invention may be utilized in the production of a press for compressing materials in the manufacture of tiles and other ceramic articles, and, further, that said invention may be adapted for use in any art or relation wherein it is, or may be, desirable to control the travel of a plunger so as to regulate the pressure exerted thereby or to eject the pressed articles from the forming die, or to control both the pressure and the ejection of the formed product.

A salient feature of the invention is a friction drive for the plunger, having associated therewith means for controlling at will the travel of said plunger, whereby the pressure exerted by the plunger upon the material may be regulated with accuracy. The employment of a friction drive eliminates gears ordinarily employed, whereby the tendency to strip the gears is wholly overcome, and economy of repairs and uninterrupted service of the press are attained.

A further feature of the invention consists of an expelling plunger and die plate operable within the die shell or box, in combination with a plurality of lift rods movable with said expelling plunger and die plate, said lift rods cooperating with the power operated head of the pressure plunger in such manner that upon the withdrawal of the plunger from the die shell said lift rods are actuated for lifting the expelling plunger and the die plate within the die shell in a manner to automatically eject the formed or compressed article from said die shell, whereupon the compressed article is lifted to the level of the die shell, and may thereafter be removed easily by a manual operation, or otherwise. The ejecting means

are unitary with the press, and are operated automatically by the press mechanism and in unison therewith, so that the cycle of operations are performed automatically to effect the compression of the material within the die shell and the ejection of the compressed material from said die shell, thus eliminating a no inconsiderable amount of hand labor hitherto required in presses for the production of saggers and other clay products.

Another feature of the invention pertains to means whereby the die shell may be charged with material easily and rapidly, and the compressed material removed from the die without interference by the compressing plunger and the overhead mechanism of the press.

A further feature is to locate the manual control for the friction drive within convenient reach of the attendant workman.

A further feature is to so construct the machine that various adjustments may be made with facility in order to adapt the press for the manufacture of different size products.

A further feature is to facilitate adjustment and minimize repairs, thus attaining economy in the time and labor required for the maintenance of the press in service condition.

Other functions and advantages of the invention will appear from the following description taken in connection with the accompanying drawings, wherein—

Figure 1 is a front elevation of a power operated manually controlled press embodying this invention.

Figure 2 is an elevation looking at the right of Figure 1.

Figures 3 and 4 are views in horizontal cross section taken in the planes indicated by the dotted lines 3—3 and 4—4 respectively of Figure 1.

Figure 5 is a detail vertical section illustrating the means for coupling the non-traveling rotary screw spindle to the driven element of the friction drive.

Figure 6 is a detail plan view of the expelling plunger associated with the lift rods.

Figure 7 is a vertical sectional elevation of said expelling plunger.

Figure 8 is a detail perspective view of the feed nut for the screw spindle.

Figure 9 is a detail section of means for controlling the action of the friction drive whereby the pressure exerted by the compression plunger may be regulated as required.

The press frame for the various operating parts may be of any desired construction, but as shown herein it embodies a base A, column housings B, a column head C, column rods D positioned within the column housings, and upstanding brackets E extending from the column housings above the column head C, the several parts being solidly united in a desired manner to result in a structure of a substantial nature. The base A is provided with depending legs a; the column housings are erected upon said base and solidly attached thereto, each column housing being of hollow or channel cross section (see Figures 3 and 4) to serve as housings for the column rods, said column rods extend through the base and the column head so as to be fixedly secured in place, and the brackets E are bolted to the column housings so as to afford a substantial support for bearings e e' of the main drive shaft F.

Said main shaft is positioned horizontally across the upper part of the press, the end portions of said shaft protruding from the respective bearings e e' so that a driving element, such as pulley f, is mounted directly on the shaft.

The base A carries or supports the die box or shell G, shown in dotted lines Figure 1, the same being of such form and capacity as to mold the article to be produced, such as a sagger. The base is slotted or apertured for the accommodation of the expelling plunger H, see Figures 1 and 7, the latter being unitary with a lower crosshead h, Figures 1, 6 and 7.

The expelling plunger is shown as being of hollow formation and provided with a crosshead h, with apertures h' in the top thereof, and with grooves h² interiorly thereof.

The top of the base A is provided with depending webs a², see dotted lines in Figures 1 and 2, between which plunger H with its crosshead h are adapted for vertical movement with respect to the die shell and said base. The opposite side portions of the plunger and crosshead are inset to produce the parallel grooves h², and in these grooves are fitted key plates i i provided on the base and the depending ribs a² thereof, said key plates i fitting in the grooves h² so as to guide the expelling plunger in its vertical travel relatively to the base and the die shell. The expelling plunger is of such shape and dimensions as to co-operate with the die shell in molding a sagger; but in the lowermost position of the plunger H it rests close to or at the

bottom for the die box, the drop of said plunger being arrested by suitable stop devices.

The lower plunger carries a die plate I, see dotted lines in Figure 1, said die plate 70 being demountable at will therefrom, as required.

Said plunger H is operated by lift rods K which are shown as passing through openings in the crosshead h of said plunger, said rods extending upwardly from the base A through which the rods are free to slide. The upper ends of the lift rods are externally threaded at k, and said threaded ends pass loosely through openings provided in the movable crosshead L, the lift rods being provided at their upper ends with adjusting and jam nuts k' for suspending the rods from said crosshead in a manner to cause the rods K and the plunger H to partake of the vertical travel of crosshead L under certain conditions, whereas under other conditions the crosshead L is free to move up and down without effecting the position of the lift rods.

The movable crosshead L is positioned between column housings B and column rods D, and to the ends of said crosshead L are bolted guide members L' which are fitted slidably upon the column rods D, see Figures 1 and 3, whereby the crosshead is limited to rectilinear movement intermediate the column guides. Said crosshead carries a suitable compression plunger L², see dotted lines in Figure 1, and the crosshead is centrally perforated at l (Figure 1) to loosely receive the lower portion of a screw spindle M. To the upper side of the crosshead is fixedly attached a nut housing m in which is mounted a tapped nut m' into which nut is screwed the threaded part of spindle M, the relation of the nut to the housing and to the spindle being such as to provide for a certain lost motion in the action of the parts during the compression of the clay material 110 within the die shell.

The screw M is power driven by the action of a reversible friction drive, presently referred to, but this power screw is mounted in the column head C so as to be restrained from traveling motion while perfectly free to rotate. The upper part of the spindle is smooth and plain, (being nonthreaded), and it passes through a bushing n provided in the column head C. Said spindle is provided above its screw part with a thrust collar n' adapted for contact with a roller thrust bearing n² which is between the thrust collar n' and the under side of the column head C. Above the thrust collar and roller thrust bearing said spindle is provided with a key slot n².

The plain part of the screw spindle extends above the column head, and upon this protruding upper part is fitted the friction 130

member O and its hub o, the latter being provided with key slots o' (see Figure 5) so positioned that they are in register with the key slot n² of the spindle, thus making provision for the reception of a key O' (Figure 5) for locking the friction member O in fixed position upon the screw spindle and making provision for taking up wear in the parts, although I may use one or more set 10 screws o³ (Figure 1) for the attachment of the friction member O rigidly to screw spindle M.

In this invention I employ a friction drive consisting of the members O, P, P' as a substitute for the usual bevel gears, and have associated with said friction drive manually operable means conveniently located for the workman for controlling the travel of the compression plunger L² whereby the 20 pressure may be regulated under the absolute control of the attendant workman notwithstanding the plunger is initially power operated, to the end that the clay material may be subjected within the die to the requisite pressure suited to the condition or character of such material and with the same facility with respect to pressure regulation as obtains in the compression of clay material by the action of hand operated presses. 25 The members P P' are composed of disks having inclined faces covered with appropriate wear resisting friction material such as tarred fibre, and the members P P' are rigidly mounted on the drive shaft F so as to face each other, each of said disks being adapted for frictional contact with the beveled friction face of the cast iron member O. The facing disks P P' are of the same diameter, said disks being smaller than 30 the disk O on the screw spindle. Said facing disks are relatively spaced on the shaft F for a distance which, in the neutral position, allows both disks to be separated a slight distance from the face of the driven 35 disk O, but the shaft F is mounted in its bearings e e' to be capable of a limited sliding movement therein as well as to be free to rotate in said bearings.

The means for imparting sliding movement to drive shaft F, shown in Figures 1, 2 and 9 comprises a sleeve or bushing Q, collars r r', an arm s, a link rod s', a rock shaft t, and a lever T, see Figures 1, 2 and 9. The sleeve or bushing Q is fitted loosely 40 on an end portion of shaft F, and between the collars r r', the latter being made fast with said shaft, said sleeve fitting in the bearing e' so as to slide and turn therein. The sleeve is shown as having a stud or 45 screw u working in an inclined or cam slot u' of the bearing e' (see Figures 1 and 9), and thus a rotative movement of the bushing is converted by the coaction of the stud and cam groove into a sliding motion, 50 which sliding motion of the bushing acts

on the collar r or r' to impart a limited sliding motion to the shaft F, whereby one friction member as P is shifted into contact with friction member O when the other friction member P' is shifted out of contact with O, and vice versa, dependent upon the direction in which bushing Q is rotated, or the shaft may be shifted to a neutral position wherein both fibre coated member P P' are free from contact with cast iron friction 70 disk O. Non-rotating bushing Q is provided at one end with arm s, to which is pivoted the link rod s', the lower end of the latter being pivoted to a short arm t' provided on the rock shaft t, which rockshaft is journaled in suitable bearings t² off one column housing B and bracket E. Lever T is attached to the rock shaft in a position convenient for the operator to grasp and operate it, said lever having the usual latch v adapted to 75 have locking engagement with a fixed quadrant v'.

The bushing Q and the parts co-operating therewith constitute a quick acting means for imparting sliding movement to the drive 80 shaft F, for the purpose of enabling the operator to bring the power mechanism into action with facility and to stop or reverse the direction of rotation of the screw easily and quickly as the conditions of service may 85 require or demand.

In my press the friction drive is associated with a rotary pressure screw acting to impart movement to the compression plunger solely by the rotative motion of said pressure 90 screw, in contradistinction to other presses wherein the plunger is given a vertical movement by an up and down motion of the pressure screw, it being noted that in my press the screw spindle M is so mounted 95 that it is incapable of vertical movement relatively to the press frame or to the compression plunger.

In operation, with the plungers H L² and the crosshead L in the raised positions 100 shown in Figure 1, the operator deposits the material upon the die plate I of the lower plunger, there being ample space between the die plate and the compression plunger for the introduction of the material and in 105 the required quantity without interference from any of the working parts of the press mechanism. The control lever T is now operated to shift F in one direction in order to bring one friction member P or P' into 110 contact with friction disk O, thus applying the power to the screw spindle for driving the latter, the rotation of said spindle acting on the nut m' to feed the crosshead L downwardly, thereby lowering the 115 pressing mechanism including the compression plunger, the lift rods, the expelling plunger, and the die plate. The adjusting and jam nuts k' on the lift rods are so positioned that the lift rods and the lower 120

130

plunger are permitted to drop down until said lower plunger reaches a point at which no further downward movement of said lower plunger can take place, but as the lift rods are fitted loosely in the upper cross-head L, the continued rotation of the screw spindle by the action of the power operated friction drive causes the crosshead L and and compression plunger L² to continue 10 the downward movement, the crosshead L sliding relatively to the lift rods K and the compression plunger L² acting upon the material confined within the die shell so as to compress the said material and form 15 the same into the required product. During the downward movement of the compression plunger, the power driven mechanism is under the immediate and direct control of the attendant who is able by shifting the 20 shaft F to move the friction member thereon into more or less intimate contact with the friction disk O, whereby the power applied by the driving mechanism is controllable for regulating the pressure as dictated by the 25 judgment and skill of the attendant workman.

The material having been formed and compressed within the die shell, the operator reverses the motion by shifting lever T so as 30 to slide shaft F in a direction for the other friction member to contact with friction disk O, thus driving the screw spindle in a direction to act on the nut for lifting the crosshead L. Upon the ascent of the cross- 35 head, the compression plunger is withdrawn from the die shell, but at this period the crosshead slides on the lift rods K, so that the rods and the expelling plunger are at rest until such a time elapses that the cross- 40 head contacts with the nuts k' of the lift rods, whereupon the continued upward movement of the crosshead operates to elevate the rods K and plunger H, the latter operating within the die shell for lifting the 45 formed and compressed product to the top of said die shell, from whence the product can be removed as desired.

It will be noted that the press mechanism is controlled by a single hand lever 50 acting to impart sliding motion to the power shaft through a quick acting thrust bushing mounted in one of the side brackets. This drive shaft is shiftable at the will of the operator so as to assume 55 a neutral position wherein friction members P P' are free from the friction disk O and both plungers L² and H are at rest, whereas the drive shaft is rotating freely in its bearings. By moving the lever 60 T in one direction, one friction member acts to impart motion through the mechanism described for the elevation successively of the compression plunger and the ejecting plunger, whereas a reverse motion of the lever so controls the mechanism that the ex-

pecting plunger and the compression plunger are moved downward successively and at the requisite intervals to compress and form the material into the desired product within the die shell. 70

Having thus fully described the invention, what I claim as new and desire to secure by Letters Patent is:

1. Pressing mechanism including a compression plunger, a feed nut and a rotative screw whereof said screw is free from endwise or traveling movement and acts by its rotative motion to impart sliding motion to the plunger, and a friction drive co-operating with said screw for imparting rotative 75 motion only thereto.

2. Pressing mechanism including a compression plunger, a feed nut and a rotative screw whereof said screw is restrained from endwise motion and acts by its rotative motion to impart sliding motion to said plunger, a power shaft, a friction drive intermediate said power shaft and the rotative screw, and means controllable at will for applying the power of said shaft to said 85 rotative screw for regulating the pressure applied by the compression plunger for the material under treatment. 90

3. Pressing mechanism embodying a slide- 95 able crosshead, a compression plunger carried thereby, a feed nut and rotative screw whereof the screw is restrained from endwise movement and co-operates with said feed nut for the rotative motion of the screw to impart sliding motion to the crosshead 100 and the compression plunger, a drive shaft mounted for shifting motion in its bearings, a friction drive intermediate said drive shaft and the rotative screw, and means controllable at will for imparting sliding motion to the drive shaft for reversing the 105 rotative screw and for regulating the application of power by said screw to the compression plunger. 110

4. Pressing mechanism embodying a cross- 110 head, a compression plunger carried thereby, a co-operating feed nut and rotative screw for imparting slidable motion to the crosshead, a power shaft mounted for sliding motion in its bearings, a friction drive 115 intermediate the power shaft and the screw for imparting rotative motion to the latter, and operating means controllable at will and including a quick acting element for imparting sliding motion to the power shaft. 120

5. Pressing mechanism embodying a cross- 125 head, a compression plunger carried thereby, a co-operating feed nut and rotative screw for imparting slidable motion to the crosshead, a power shaft mounted for sliding motion in its bearings, a friction drive intermediate the power shaft and the screw for imparting rotative motion to the latter, a cam controlled bushing co-operating with 130 said power shaft for imparting sliding mo-

- tion thereto, and a manually operable lever linked to said bushing for rotating the latter.
6. Pressing mechanism including a cross-head carrying a compression plunger, a die, an expelling plunger movable within said die, and means actuated by the movement of the crosshead for imparting motion to said expelling plunger relatively to said die.
- 10 7. Pressing mechanism including a cross-head carrying a compression plunger, a die, an expelling plunger movable within said die, and means operatively connecting said expelling plunger with said crosshead for actuating the expelling plunger with a definite lost motion relatively to the movement of the compression plunger.
- 15 8. Pressing mechanism including a die, an expelling plunger movable therein, a cross-head carrying a compression plunger, and connecting means intermediate the expelling plunger and said crosshead for imparting motion to said expelling plunger by the travel of the crosshead, said connecting means operating upon the withdrawal of the compression plunger from the die to impart motion to the expelling plunger within said die.
- 20 9. Pressing mechanism including a die, an expelling plunger slidably therein, a cross-head carrying a compression plunger, and lift rods attached to the expelling plunger and slidably fitted to the crosshead whereby
- 25 said crosshead is adapted for movement relatively to the lift rods for withdrawing 35 the compression plunger from the die and subsequently thereto said crosshead acts to lift said rods and the expelling plunger relatively to said die.
10. Pressing mechanism including a cross-head carrying a compression plunger, a die, an expelling plunger, lift rods attached to the expelling plunger and fitted loosely to the crosshead, and means on the lift rods in the path of the crosshead whereby the elevation of said crosshead acts to lift the rods and the expelling plunger.
- 15 11. Pressing mechanism including a bed plate provided with guides, a die, an expelling plunger having guide ways for slidably 50 receiving said guides, a crosshead carrying a compression plunger, and means operated by the travel of said crosshead for imparting motion to said expelling plunger.
- 20 12. Pressing mechanism including a die, a crosshead, a compression plunger carried directly by said crosshead, an expelling plunger movable within the die, and means actuated by the travel of the crosshead for imparting sliding motion to the expelling 55 plunger relatively to the die and subsequently to the withdrawal of the compression plunger from said die.
- 25 In testimony whereof I have signed my name this 18th day of March, 1921.
- HARRY D. LILLIBRIDGE.
